INVENTOR
3 FREDERICK P. GATES

By John W. Chapman, Jr.

UNITED STATES PATENT OFFICE

FREDERICK PATON GATES, OF BRIXTON, LONDON, ENGLAND

PRESS FOR TENNIS AND LIKE RACQUETS

Application filed July 16, 1931, Serial No. 551,229, and in Great Britain July 26, 1930.

This invention relates to presses for tennis and like racquets and concerns a press wherein the opposed press members between which the racquet is to be clamped, are drawn together by means of levers provided on one of the said members, said levers having their outer ends engaged with posts, links or the like or being equivalently connected to the opposed clamping members and means being provided for exerting a downward pressure on the inner ends of said levers, to produce upward movement of their outer ends and consequent drawing together of the opposed members by the movement imparted to the posts, links or equivalent connecting devices.

The present invention provides a press for tennis and like racquets wherein each of the press members comprises a frame-like structure, two or more of the frame portions of the upper structure embodying a pair of spaced-apart parallel portions having levers engaging posts or links upstanding from the lower press frame portions, and operating means adapted to exert a downward pressure on the levers to rock the latter and cause the press members to be drawn together.

To reduce the amount of movement required to be imparted to the inner ends of the levers to produce a given movement of their outer ends, the fulcrum points of the levers are disposed in the proximity of the center of the length of the levers, and the operating means is located within the enclosed area of the press members and is adapted to simultaneously operate the posts or links associated with the frame members.

For a ready understanding of the invention, reference is to be had to the following description and accompanying sheet of drawing, wherein:

Figure 1 is a plan view of a press constructed in accordance with the invention, certain parts of the press being omitted for clearness.

Figure 2 is a vertical sectional view taken on line $x-x$ of Figure 1 with arms 9 in elevation.

Figure 3 is a vertical sectional view taken on line $y-y$ of Figure 2.

Figure 4 is a view similar to Figure 2, but showing a slight modification thereof.

Like numerals of reference indicate corresponding parts in the several figures.

In carrying out the invention, and referring to the drawing, the upper press member consists of a quadrilateral frame comprising two spaced-apart parallel portions constituted by box-like members 1, 1 braced together at their ends by horizontally disposed stays 2, whilst the lower press member consists of a quadrilateral frame comprising two spaced-apart parallel portions constituted by inverted trough-like members 3.

In the ends of each inverted trough-like member 3 there is fixedly secured a post 4 which upstands therefrom and freely extends through the bottom wall 5 of the box-member 1 thereabove, springs 6, which encircle the posts 4, normally maintaining the press members pressed apart from one another.

The posts 4 terminate in inwardly facing hook-ends 7 in which engage fingers 8 on the outer ends of the levers 9 housed in the box-like members 1, 1, said levers 9, on their undersides, being each bevelled in opposite directions to form a fulcrum point 10, which is disposed approximately centrally in the length of the lever and engages and is slidable on the bottom wall 5 of its box-member 1, 1, the inner ends of the levers 9 overlapping one another, as shown in Figure 2.

An operating member is provided on the top member of the press, said operating member consisting of a handle 11 of arch-like form, the ends of which are pivotally mounted in the side walls of the box-members 1, 1, the said ends being formed with

cranks 12, cams or the like, adapted to bear on the inner ends of the levers 9.

The handle 11 is adapted to be swung through about 180 degrees and in so doing 5 the cranked or cam portions 12 thereof will impart a downward movement to the inner ends of the levers 9 to rock the latter and cause the press members, through the posts 4, to be drawn together.

10 The degree of movement which the handle 11 is allowed is governed by the stays 2 which connect together the parallel portions or box-members 1, 1 of the upper press member and against which said handle 11 15 is adapted to bear in its respective pressure-applying and released positions.

The parallel portions of both the upper press member and the lower press member are of unequal length so that when the parallel 20 portions of each press member are stayed together, the said press members constitute quadrilateral structure of symmetrical trapezoidal formation.

Referring now to the arrangement of press 25 shown in Figure 4, the construction of the upper and lower press members is similar in all respects to that previously described, two variations are shown. Firstly, the levers 9 of the upper press member are made 30 shorter in length and their inner ends are pivotally connected together by a bridge piece 13 on which the cranked portion 12 of the operating handle 11 is adapted to bear. Secondly, the fulcrum point for each 35 lever 9 is constituted by a stud 14 upstanding from the bottom walls 5 of the box members 1, 1, said studs engaging the undersides of the levers 9 and centrally in the length of the levers. It is to be understood 40 that either of these variations may be substituted for the equivalents shown in the first described arrangement.

I claim:—

1. A press for tennis racquets comprising 45 upper and lower quadrilateral frames, posts at the four corners of the lower frame extending loosely through the upper frame, yieldable means urging the frames apart, a pair of substantially alined levers at each 50 of two opposite sides of the upper frame, each lever at its outer end engaging a related post and at an intermediate point being fulcrumed on the upper frame, an operating member pivoted at its ends in the 55 sides of the upper frame on which said levers are fulcrumed, and a pair of cam formations on said operating member each cooperating with the inner ends of a pair of said levers to swing them downwardly 60 thus to draw the frames together into clamping engagement with a racquet disposed therebetween by swinging movement of the operating member.

2. A press for tennis racquets as set forth 65 in claim 1 in which the inner end of one of

the levers of each pair overlaps the inner end of the companion lever, and in which the cam formations of the operating member respectively engage the inner ends of the uppermost levers.

3. A press as set forth in claim 1 in which a separate member connects the adjacent ends of the levers of each pair, and in which the cam formations of the operating member respectively engage said members. 75
